HAROLD C. SUCKERT, OF NEW YORK, N. Y.

VACUUM FUEL-FEEDING SYSTEM FOR GASOLENE-ENGINES.

1,258,060.

Specification of Letters Patent. Patented Mar. 5, 1918.

Application filed August 27, 1915. Serial No. 47,595.

To all whom it may concern:

Be it known that I, HAROLD C. SUCKERT, a citizen of the United States, and a resident of the borough of Manhattan, city, county, and State of New York, have invented certain new and useful Improvements in Vacuum Fuel-Feeding Systems for Gasoline-Engines, of which the following is a specification.

10 In the installation of gasoline engines it has heretofore been the almost universal practice to place the gasoline or fuel tank above the carbureter in order to secure a gravity feed of the fuel from the tank to the carbureter. In the few instances in which the fuel tank has been placed below the carbureter some form of pump has been used to maintain an air pressure in the gasoline tank in order to force the gasoline up 20 to the carbureter. In other cases a vacuum pump has been used to draw the gasoline from the fuel tank to a point higher than the carbureter and to then feed the gasoline by gravity to the carbureter. This invention 25 relates to this latter type of fuel feeding means.

It is the main object of this invention to simplify the vacuum apparatus by means of which the gasoline is drawn from the tank 30 and delivered into the small gravity tank from which it is fed to the carbureter.

Another object of the invention is to dispense with all float-operated devices and to provide an apparatus which will be very 35 simple in construction and positive and reliable in operation.

Other objects and advantages of the invention will appear hereinafter.

In the drawings, Figure 1 is an outline 40 view of my improved fuel feeding system applied to a gasoline engine;

Fig. 2 is a vertical central sectional view of the vacuum pump and gravity feeding tank, showing the parts in the position 45 which they occupy when gasoline is being drawn from the storage tank into the pumping chamber; and

Fig. 3 a similar view showing the parts in the position which they occupy when the 50 gasoline is being delivered from the pumping chamber into the gravity feed tank, the pumping chamber being cut off from communication with the suction apparatus.

Referring to the various parts by numerals, 1 designates the engine, 2 the manifold

through which the gas from the carbureter is conducted to the engine intake; 3 the carbureter and 4 the fuel tank. The gravity feed tank 5 is located in any convenient position above the carbureter, preferably under 60 the hood of the engine, as indicated in Fig. 1. The lower end of this gravity feed tank is connected by a pipe 6 to the carbureter and through this pipe fuel is fed by gravity. The fuel tank 4 is connected to the pumping 65 apparatus through a pipe 7 and said apparatus is connected to the manifold of the engine through a pipe 8.

Secured to the top of the tank 5 is a rigid cap or head 9. This head is formed with a 70 central downwardly tapered valve chamber 10 whose downwardly inclined wall forms a valve seat. Closing the valve chamber is a top plate 11. Rigidly secured centrally to this top plate and extending downwardly 75 through the valve chamber 10 and into the tank 5 is a rigid guide and supporting rod 12, a securing and lock nut 13 being screwed on the upper end thereof and bearing against the top plate. Within the feed tank, and 80 near the upper end thereof is a pumping chamber 14. Closing the upper end of this chamber is a flexible diaphragm 15, the inner annular edge of said diaphragm being connected to a depending annular flange 16 85 formed on the head 9 within the tank 5. The outer edge of the diaphragm is rigidly secured to the upper end of the pumping chamber 14. The diaphragm 15 is sufficiently large to permit the pumping chamber to have the desired reciprocal movement, as will be hereinafter described. The lower end of the valve chamber 10 is in communication with the interior of the pumping chamber 14, as shown clearly in Fig. 2. On 90 the lower end of the supporting rod 12 is a collar 17. The lower end of this collar forms a valve seat 18. This collar is formed with a depending tubular extension 19 apertured at 20. In the bottom of the pumping chamber is secured a valve 21, said valve sliding on the extension 19 as the pumping chamber is reciprocated. When the pumping chamber is in its upper position, as shown in Fig. 2, valve 21 is seated against seat 18 95 and there is no communication between the apertures 20 and the interior of the pumping chamber. When the pumping chamber is in its lowermost position, as shown in Fig. 3, the apertures 20 are in communication with 100

105 110

the pumping chamber thereby connecting said chamber with the interior of the feed tank, as shown clearly in Fig. 3.

Sliding on the supporting rod 12 near its upper end is a sleeve 22. This sleeve is rigidly connected by tubular horizontal arms 23 with the outer wall of the pumping chamber so that said sleeve moves up and down with said chamber. In each arm is arranged a spring 24, each of said springs serving to press a catch ball 25 into recesses 26 formed in the supporting rod. There are two sets of recesses 26, one above the other, said recesses limiting the reciprocal movement of the pumping chamber. Between the collar 17 and the lower end of the sleeve 22 is a coil spring 27, said spring serving to hold the pumping chamber in its upper position when said chamber is empty and until it has received a predetermined quantity of gasoline.

In the valve chamber 10 is arranged a downwardly tapered valve 28, said valve being adapted to seat on the downwardly inclined wall of the valve chamber. This valve is carried by a depending tubular extension 29 which is adapted to slide on the central supporting rod 12; the lower end of said tubular extension being in position to be engaged by the upper end of the sleeve 22 when the pumping chamber is at, or near the end of its upward movement. The fuel pipe 7 is connected to the valve chamber through the port 30; and the exhaust pipe 8 is connected to the valve chamber through a port 31. When the valve 28 is seated, it closes ports 30 and 31. Within the valve chamber 10 and surrounding the guide rod 12 is a light coil spring 32, which assists in seating the valve 28 when the pumping chamber is in its lower position. The operation of the apparatus may be briefly described as follows:

When the pumping chamber is empty of gasoline it is in its upper position, as shown in Fig. 2, and valve 28 is raised from its seat. In this position of the parts, pipes 7 and 8 and valve chamber 10 are in communication with the interior of the pumping chamber.

When the engine is in operation there will be sufficient suction through pipe 8 to exhaust air from the pumping chamber 14. This will result in a suction through pipe 7 sufficient to lift the gasoline from the fuel tank 4 into the valve chamber 10. The gasoline will flow from the valve chamber into the pumping chamber and will accumulate therein until its weight releases the catches 25, whereupon the tank will drop until the apertures 20 are in communication with the lower end of said chamber. At the same time the catches 25 will engage the lower set of recesses 26 and hold the pumping chamber in its lower position until the accumulated gasoline has passed through the apertures

20 into the tank 5. When the weight of gasoline has been sufficiently reduced a spring 27 will force the pumping chamber upwardly until the catches 25 engage the upper set of notches and the valve 21 has seated against valve seat 18, thereby closing the outlet apertures 20. In this upward movement of the pumping chamber the sleeve 22 engages the lower end of the extension 29 of valve 28 and lifts said valve from its seat thereby restoring communication between pipes 7 and 8 and the interior of the pumping chamber.

When the pumping chamber is in its lower position air will pass from the feed tank into the pumping chamber through the apertures 20. The feed tank 5 is vented at its upper end in a suitable manner.

Should gasoline accumulate in the feed tank 5 to such an extent as to prevent the draining of the pumping chamber, said chamber would remain in its lower position and the valve 28 would, of course, remain closed and there would be no further accumulation of gasoline in the pumping chamber until said chamber had been drained and moved to its upper position. This effectively prevents the accumulation of an excess quantity of gasoline in the feed tank. It is therefore clear that the chamber 14 serves as a means for limiting the amount of gasoline which may be accumulated in the feed tank. If the apertures 20 are sealed by gasoline in the feed tank air cannot pass to the interior of the pumping chamber and consequently gasoline therein cannot flow through said apertures to tank 5. It is also clear that gasoline can flow into tank 5 from the pumping chamber only when the apertures 20 are unsealed; so that the immersion of the lower part of the pumping-chamber in the gasoline accumulated in the tank will not neutralize the weight of the gasoline in the pumping-chamber sufficiently to allow the pumping-chamber to prematurely ascend.

The apertures 20 are so spaced from the valve seat 18 that the valve 28 will be closed before the said apertures are opened. It is manifest that these valves should be properly timed in order to prevent air passing up into the tank 14 while the exhaust port 31 is open. By locating the apertures 20 a considerable distance below the valve seat 18 the catches 25 will be wholly released from their coacting depressions 26 before the said apertures are opened. It is desirable to hold the entire weight of the gasoline in the tank 14 for the purpose of releasing the catches and moving the tank to its lower position. For that reason it is desirable that the apertures 20 be held closed until the catches 25 are wholly free from the notches 26.

What I claim is:

1. A fuel feeding apparatus comprising a fuel tank, a carbureter, a gasoline engine, a feeding tank above the level of the car.

- bureter, a pumping chamber formed with a flexible diaphragm in one of its walls, means connecting the interior of said pumping chamber with the intake side of the engine,
- 5 means connecting the said chamber with the fuel tank, means connecting the lower end of the feed tank with the carburetor, and means whereby the weight of a predetermined amount of gasolene in the pumping
- 10 chamber will flex said diaphragm and close communication with the fuel tank and the engine, and open communication between the pumping chamber and the feed tank.
2. The combination of a feed tank, a pumping chamber, a diaphragm in one wall of said pumping chamber, suction operated means for accumulating fluid in said chamber, valve mechanism controlling communication between the feed tank and the pumping chamber and the suction operated means, means whereby the weight of a predetermined accumulation of fluid in the pumping chamber will close communication with the suction operated means and open communication between the pumping chamber and the feed tank, and means operating after the discharge of fluid from the pumping chamber to restore communication between the pumping chamber and the suction operated means.
3. The combination of a feed tank, a vertically movable pumping chamber therein, a flexible diaphragm forming the top of said pumping chamber, said chamber being provided with a fluid inlet port and an exhaust port leading from its top, yieldable means for holding the pumping chamber in communication with the fluid inlet and the exhaust outlet whereby the weight of the accumulated fluid in the pumping chamber will flex the diaphragm and depress said chamber and close communication between said chamber and the exhaust outlet and open communication between the said chamber and the feed tank, said yieldable means embodying devices for raising the pumping chamber after the discharge of fluid to thereby restore communication between said chamber and the exhaust outlet.
4. In an apparatus of the class set forth, the combination of a feed tank having a closure head provided with an inlet port and an exhaust port and a passage leading from said ports to the interior of the feed tank, a valve controlling said passage and said ports,
- a vertically-movable pumping chamber located within the feed tank and adapted to open said valve when the pumping chamber is at its highest point, the upper end of said pumping chamber being closed by a flexible diaphragm connecting the chamber to said head, means whereby the weight of the accumulated fluid in the pumping chamber will depress said chamber and permit said valve to close and also to open communication between the pumping chamber and the feed tank, and means for raising the pumping chamber to open said valve after the discharge of fluid from the pumping chamber into the feed tank.
5. The combination of a feed tank, a vertically movable pumping chamber therein, a flexible diaphragm forming the top of said pumping chamber, said chamber being provided near its top with a fluid inlet port and an exhaust port, a valve controlling said ports, yieldable means for holding the pumping chamber in its upper position, means whereby the chamber in its upper position will hold the said valve open, means opening communication between the pumping chamber and the feed tank when the accumulated fluid in the pumping chamber overcomes the yieldable holding means and depresses said chamber, and means for closing the said valve when the pumping chamber is depressed.
6. The combination of a feed tank, a vertically movable pumping chamber therein, a flexible diaphragm forming the top of said pumping chamber, said chamber being provided near its top with a fluid inlet port and an exhaust port, a self-seating valve controlling said ports, yieldable means for holding the pumping chamber in its upper position, means whereby the chamber in its upper position will hold the said valve open, means opening communication between the pumping chamber and the feed tank when the accumulated fluid in the pumping chamber overcomes the yieldable holding means and depresses said chamber, and means for raising the pumping chamber after the discharge of fluid to open the self-seating valve and thereby restore communication between the pumping chamber and the inlet and exhaust ports.

In testimony whereof I hereunto affix my signature.

HAROLD C. SUCKERT.
